GRATING MACHINE

David Pelton Moore, Forest Hills, N. Y., assignor to Premium Merchandising Corp., New York, N. Y.

Application December 9, 1942, Serial No. 468,356

6 Claims. (Cl. 146—3)

The present invention relates to improvements in grating machine, that is to a machine for grating or rasping the outer rind from citrus fruits, such as lemons, grapefruit and oranges, one object of the invention being the provision of a machine which will act upon the fruit fed in a continuous stream thereto, and which will grate the outer rind from the fruit to a desired depth so that such grated rind is in the best possible state for treatment to remove the pectin, pectose, pectase and essential oils therefrom.

Another object of the present invention is the provision of a machine which is adjustable to act upon various sized or graded fruits, so that one machine with replaceable parts results, and one that can speed up production and receive and act upon the fruit which is fed continuously one at a time thereto.

Still another object of the present invention is the provision of a simple, durable and comparatively inexpensive machine of this type, and which is thoroughly practical and efficient in use.

In the accompanying drawing—

Figure 1 is a cross section through a complete machine made according to and embodying the present invention.

Figure 2 is a top plan view partially in section and broken away to more clearly show the various component parts.

Referring to the drawing, the numeral 1 designates a base upon which is mounted four legs or standards 2, each of which is made in two sections 2'—2'', attached adjustably together at 3, so that the length of the legs may be increased and decreased for various diametered fruits.

An annular ring or base plate 4 is supported by the legs 2, and is provided with the internal lip 5, which forms a supporting bearing for a rotatable disk 6, having the hoppered inlet concentric opening 7 through which the fruit is fed to the machine.

A gear 8 is fast to the hopper, and forms the medium through which the disk 6 is rotated, the inner face 6' of the disk being a grating surface, either formed integral with the disk or a plate formed with grating means detachably attached to and carried by the disk. This disk is rotated in the direction of the arrow, Fig. 2, through the medium of the gear 9 carried by the gearing casing 10, and this gear meshes with a gear 11, carried upon the upper end of the vertical shaft 12, which is made in two sections 12'—12'', attached by the adjusting sleeve 20, and the purpose of which is to provide for the vertical adjustment of the abrasive disk 6, as will presently appear.

A bearing support 13 has mounted therein a vertical shaft 14, which is fast at its upper end to the lower abrasive disk 15, whose abrasive surface 16 is here shown as being slightly depressed at the center, so as to provide a space between the two disks 6 and 15 deeper at its center and gradually narrowing toward the periphery of such space. This permits better action upon the fruit, and insures a better and cleaner grating of the outer rind from the fruit, and a more uniform grated fruit as the same is projected by centrifugal force through the circumferential peripheral space into the hopper 21.

A pulley 17 forms one means of drive for the shaft 14 and the lower disk 15, while a cross belt 18 receives its motion from the shaft 14 and drives a pulley 19 on the lower section 12'' of the gear drive shaft 12.

It is desirable that the disk 6 be driven in an opposite direction to the disk 15, as indicated by the arrows in Fig. 2, and by the change of the gears 9 and 11, the disk 6 may be rotated at selected speeds in accordance with the object to be obtained in grating of the fruit, that is the greater its speed, the more fruit will be acted upon.

The fruit and gratings receiving hopper may be supported in any desired manner, and is so constructed, as to receive the fruit and gratings at any point of the circumference of the machine and deliver the fruit and gratings either together at one point for separation, or the gratings may be screened simultaneously with the ejection of the fruit into the hopper.

In putting this machine into practice, the legs 35 and the shaft 12 are adjusted to the sorted sized fruit to be acted upon, and the disks are then set in motion. The fruit should be thoroughly washed and dried before being fed one at a time into the hopper 7. Proper delivery means is to be provided to insure a continuous feed of the fruit to the machine, and with 3 inch fruit and 42 inch disks, rotated at 100 R. P. M. not less than 12 fruit to a second can be grated and delivered into the hopper 21.

Inasmuch as the grated outer rind, the depth of which is determined by the distance that the disks 6 and 15 are separated, is of a uniform size, it needs no further comminuting, and is ready as it leaves the machine to be treated to extract the pectin, pectose, and pectase, or any of the essential oils that may be desired, and which form part of such rind.

The grated fruit is ejected as white globes, and is ready for juicing, sectioning or may be shipped as is, for use in the home or for juicing locally. 55 By this method, the fruit is sanitary, as the rind

is thoroughly washed and dried before entering this machine, and is not contaminated during the grating operation. This machine also being a machine of the type to insure continuous operation is a real production machine for use in packing houses, and having a few parts and no knives to sharpen, is a very essential and practical machine for the purposes set forth.

What is claimed is:

1. A fruit rind grating machine, including in combination vertically adjustable supporting means, an annular member carried thereby, a rotary disk mounted in and carried by the annular member, a secondary rotary disk mounted below and spaced from the first disk and providing therewith a fruit receiving space, said first disk being provided with a concentric fruit adit opening, and means for rotating the disks simultaneously but in opposite directions.

2. A fruit rind grating machine comprising a base, a plurality of vertically adjustable supports mounted thereon, an annular base plate supported at the upper ends of said supports, an abrasive disk mounted in said base plate for rotary movement, a second abrasive disk disposed below and in spaced relation to the first disk, the first disk being provided with a central fruit adit opening leading into said space, the vertical adjustment of the supports regulating the size of the space between the disks to accommodate various sized fruits, a main shaft for rotating the second disk, a second shaft operatively connected to the main shaft, and means connecting the second shaft to the first disk, whereby the first disk is rotated in a direction opposite to but simultaneously with the second disk.

3. A fruit ring grating machine as claimed in

claim 2, wherein the means connecting the second shaft to the first disk includes a gear connected to the upper central portion of the first disk adjacent the adit opening, a vertical shaft operably connected to the second disk operating shaft, and gears connecting the upper end of such vertical shaft to the first gear.

4. A fruit rind grating machine, including in combination a supporting structure, an annular supporting disk mounted upon the supporting structure, a grating disk mounted for rotation in said annular disk and provided with a central adit opening for the fruit, a concentrically disposed main shaft having its upper end spaced from the grating disk, a second grating disk bodily supported by the said main shaft and having its grating surface opposed to and spaced from the first grating disk to provide a peripherally disposed outlet for the grated fruit and grated rind, and means for driving the first grating disk from the main shaft.

5. A fruit rind grating machine as claimed in claim 4, wherein the latter means includes a fruit directing hopper concentrically of the adit opening, a gear attached to and surrounding said hopper, and gears operably connected to said latter gear and the main shaft, whereby the two disks are rotated simultaneously in opposite directions.

6. A fruit rind grating machine as claimed in claim 4, wherein an annular fruit and rind receiving hopper is disposed below the annular supporting disk and has an apron extending above the upper face of the second grating disk to receive the fruit and grated rind expelled through the peripheral space between the two grating disks.
